UNITED STATES PATENT OFFICE.

VALENTINE G. SCHUCK, OF NEW YORK, N. Y., ASSIGNOR TO THE SUTRO BROS. BRAID COMPANY, OF SAME PLACE.

DESIGN FOR A BRAID.

SPECIFICATION forming part of Design No. 22,614, dated July 18, 1893.

Application filed June 6, 1893. Serial No. 476,784. Term of patent 14 years.

To all whom it may concern:

Be it known that I, VALENTINE G. SCHUCK, of the city, county, and State of New York, have invented and produced a new and original Design for a Braid to be Used by Way of Ornamentation and in Trimming Garments, &c., of which the following is a specification, reference being had to the accompanying drawing, showing a part thereof.

10 The design is applied to a flat braid presenting on both sides a uniform appearance and the leading characteristics are consecutive longitudinal rows of double arrow heads which appear also in opposite diagonals across 15 the face of the braid. These arrow heads divide two adjacent longitudinal strands into blocks or fields having parallel sides, one end presenting an outwardly and the opposite end an inwardly projecting angle; such blocks or 20 fields appearing in rows longitudinally and in opposite diagonals across the face of the braid.

In the drawing *a, a, a*, represent strands running parallel to each other throughout the entire length of the braid.

25 *b, b*, are either cords or strands which run in pairs and hold strands *a, a*, in place, *b, b*,

crossing a longitudinal strand *a*, diagonally at regular intervals divide it apparently into parallelograms, and an adjacent longitudinal strand being crossed at the same point in an opposite diagonal is likewise divided, and the two parallelograms joining constitute the block or field herein above mentioned, and *b, b*, crossing adjacent strands at the same point in opposite diagonals presents the appearance of the double arrow head or cuneiform interlocking figure *c*.

The leading features presented to the eye by a braid containing my design are longitudinal and diagonal rows of double arrow heads or cuneiform figures, and longitudinal and diagonal rows of blocks or fields herein described, all as clearly illustrated in the accompanying drawing.

What I claim is—

45 A design for a braid as herein shown and described.

VALENTINE G. SCHUCK.
